CLAIM

The ornamental design for a display screen or portion thereof with animated graphical user interface as shown and described.

DESCRIPTION

FIG. 1 is a front view of a display screen or portion thereof with animated graphical user interface showing the first image of our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eighth image thereof;

FIG. 9 is a ninth image thereof;

FIG. 10 is a tenth image thereof;

FIG. 11 is an eleventh image thereof;

FIG. 12 is a twelfth image thereof;

FIG. 13 is a thirteenth image thereof;

FIG. 14 is another front view of FIG. 1, shown with additional broken line subject matter;

FIG. 15 is another front view of FIG. 2, shown with additional broken line subject matter;

FIG. 16 is another front view of FIG. 3, shown with additional broken line subject matter;

FIG. 17 is another front view of FIG. 4, shown with additional broken line subject matter;

FIG. 18 is another front view of FIG. 5, shown with additional broken line subject matter;

(Continued)

FIG. 19 is another front view of FIG. 6, shown with additional broken line subject matter;
 FIG. 20 is another front view of FIG. 7, shown with additional broken line subject matter;
 FIG. 21 is another front view of FIG. 8, shown with additional broken line subject matter;
 FIG. 22 is another front view of FIG. 9, shown with additional broken line subject matter;
 FIG. 23 is another front view of FIG. 10, shown with additional broken line subject matter;
 FIG. 24 is another front view of FIG. 11, shown with additional broken line subject matter;
 FIG. 25 is another front view of FIG. 12, shown with additional broken line subject matter; and,
 FIG. 26 is another front view of FIG. 13, shown with additional broken line subject matter.
 The appearance of the animated graphical user interface sequentially transitions between the images shown in FIGS. 1-13 and 14-26. The process or period in which one image transitions to another forms no part of the claimed design. The dot-dash broken line illustrates a display screen or portion thereof and forms no part of the claimed design. The even-dash broken lines in FIGS. 14-26 illustrate portions of the animated graphical user interface that form no part of the claimed design.
